H. E. MARSH

AUTOMATIC SELF FEEDING CARBURETOR

Filed March 10, 1925

Patented Sept. 15, 1925.

1,553,453

UNITED STATES PATENT OFFICE.

HOWARD E. MARSH, OF LOMPLOC, CALIFORNIA.

AUTOMATIC SELF-FEEDING CARBURETOR.

Application filed March 10, 1925. Serial No. 14,355.

To all whom it may concern:

Be it known that I, HOWARD E. MARSH, a citizen of the United States, residing at Lompoc, in the county of Santa Barbara and State of California, have invented certain new and useful Improvements in Automatic Self-Feeding Carburetors, of which the following is a specification.

The present invention relates to carburetors for internal combustion engines and the like.

The principal object of the invention is to provide a carburetor in which is incorporated means, actuated by the reduced pressure or suction at the engine intake, for automatically feeding the liquid fuel from a lower level. It is therefore especially adapted for use in automobiles, in which the fuel tank is ordinarily located in a low position at the rear of the body. In such use it combines in one structure the functions of two separate commonly employed devices, the carburetor and the so-called vacuum tank, and by so doing eliminates the duplication of certain parts necessary to the operation of both such devices. A further object of the invention is to provide a vacuum or suction fuel feed device which may be added, without great expenses, to any suitable form of standard carburetor in present use.

A still further object of the invention is to provide an efficient and inexpensive means for heating either the liquid fuel, or the mixture of vaporized fuel and air, or both, to assist the vaporization of the fuel and its proper admixture with the air. Other objects and advantages of the invention will become apparent from the following description of a preferred embodiment thereof. It should be understood, however, that the form and construction herein illustrated and described may be varied, within the limits of the claims hereto appended, without departing from the spirit of the invention as set forth in said claims.

With this in view my invention will now be fully described with reference to the accompanying drawings, wherein:

Fig. 1 is a vertical section of a carburetor embodying a preferred form of my said invention.

Fig. 2 is a plan view thereof,

Fig. 3 is a detailed side elevation of the auxiliary air inlet shutter.

In the drawings, the reference numeral 1

designates a carburetor body, having a preferably integral float chamber or liquid fuel reservoir 2, an air inlet 3, and an outlet at 4 adapted for connection with the intake pipe or manifold, not shown, of an engine. Between said air inlet and said manifold connection is the mixing chamber 5, which is preferably formed within a removable Venturi tube 6, the latter being secured in the body 1 by any convenient means, as for example a screw thread shown at 7. The usual butterfly choke valve is shown in the air inlet at 8, to enable an over-rich mixture to be formed to facilitate starting the engine, and the usual butterfly throttle valve 9 is provided above the mixing chamber 5 to regulate the quantity of gaseous fuel supplied to said engine.

The float chamber 2 contains a float 10 adapted to rise and fall with the liquid contained in said chamber, and said float operates a valve stem 11 through levers 12 fulcrumed at 13, said stem moving in the opposite direction to said float. The lower end of the stem 11 forms a needle valve 14 to control the admission of liquid fuel to the chamber 2 from a supply pipe 15 in accordance with amount of liquid contained within said chamber.

The liquid fuel passes out of the float chamber 2 through a passage 16 formed in the body 1, said passage terminating in an annular groove 17 surrounding the Venturi tube 6. Said Venturi tube is provided with an annular series of small perforations 18 through which the liquid issues, in the form of spray, into the mixing chamber 5. The liquid fuel passage 16 is preferably provided with any well known form of strainer, indicated at 19, and with a rotary valve 20, actuated by an arm 21 which is connected by a link 22 with the arm 23 of the throttle valve 9, so that the liquid fuel is controlled, by said valve 20, in substantial accordance with the gaseous fuel passing through said throttle. A drain cock 24 and a vent 24' may be provided for the float chamber 2. The construction and parts above described are well known in the art, and are common, in various forms, in many types of carburetors in present use.

A receptacle or chambered member 25 is secured to the top of the float chamber 2, preferably by a threaded connection 26, forming a cover for said float chamber. A second receptacle or chambered member 27

is secured to the top of the chamber 25, preferably by a threaded connection 28. A guide 29, in which the valve stem 11 operates, extends through said chambers 25 and 27. A valve housing 30 extends upwardly from the top of the upper chamber 27, and contains three spaced disks 31, 32, and 33, each having a central aperture formed with a valve seat. The stem 11 extends through the two lower disks or seat members 31 and 32, and is provided with valve heads 34 and 35, the head 34 controlling the aperture 31' of the lowest disk 31, and the head 35 controlling the apertures 32' and 33' of the two upper disks 32 and 33 respectively.

A suction pipe 36, connected with the intake manifold (not shown) of the engine, leads into the space between the two lower disks 31 and 32, and said space also communicates, through the aperture 31', with the upper chamber 27. The space between the two upper disks 32 and 33 is vented through the aperture 33', and is also connected with said chamber 27 by a pipe 37. A liquid fuel supply pipe 38 leads into said upper chamber 27, and a port 39 connects said chamber with the lower chamber 25. A float or flapper valve 40 controls said port to prevent back flow, of either fuel or air, from the chamber 25 into the chamber 27. The pipe 15 supplying the liquid fuel to the float chamber valve 14, leads from the chamber 25, as shown at 41.

The operation of the mechanism above described is essentially similar to that of the usual so-called vacuum tank, except that it is controlled directly by the main carburetor float 10. When the level of the liquid in the float chamber 2 drops below a predetermined point, the stem 11 is raised from the position shown in Fig. 1, by the action of the float 10 and the arms 12, thereby opening the valve 14 and the apertures or ports 31' and 32', and closing the vent 33'. This connects the suction line 36 with the upper or suction chamber 27, causing the liquid to be drawn thereinto from the supply line 38. At the same time, the liquid contained within the lower or supply chamber 25 flows, by gravity, into the float chamber 2. When the liquid in said float chamber rises to the desired predetermined level, the stem 11 is lowered to the position shown, closing the valve 14 and the ports 31' and 32' and opening the vent 33'. This cuts off the suction line 36, and vents the suction chamber 27 through the pipe 37 and the vent port 33', thereby permitting the liquid to flow from said chamber 27 through the port 39 into the supply chamber 25. The operation is then repeated.

The disks or seat members 31, 32 and 33 are preferably adjustable within the housing 30 to enable the valve heads 34 and 35 properly to cooperate therewith. Any suitable

means may be provided for adjusting said disks, but for purposes of illustration I have shown them screwed into said housing 30, and the upper and lower disks 33 and 31 are shown as provided with means for adjusting their positions, by turning them, from the outside. For this purpose said disks are provided with circumferential grooves 42 whose bottoms are formed with worm threads adapted to be engaged by horizontally disposed worms 43 rotatably mounted in the housing 30 and provided with exterior knobs, one of which is shown at 44 in Fig. 2. The valve 14 may also be formed in an adjustable seat member or disk 14' screwed into an extension 45 of the bottom of the float chamber 2. A removable plug 46 is provided to give access to said disk 14', and also to serve as a drain plug for the float chamber 2, the pipe 15, and the chambers 25 and 27.

In order to heat the mixing chamber 5 and the liquid fuel within the float chamber 2, to assist the vaporization of said fuel, I provide a passage 47 within the lower portion of the body 1, said passage having a preferably cylindrical tubular extension 48 rising into the mixing chamber 5 centrally of the Venturi tube 6. Said passage also communicates with a tubular coil 49 surrounding the float 10 within the chamber 2. Inlet and outlet connections 50 are provided, by which the passage 47 and the coil 49 may be connected with a suitable source of hot fluid, not shown, such for example as the exhaust manifold of the engine. Such hot fluid, in passing through the coil 49, heats the liquid fuel within the float chamber 2, and in passing through the passage 47 and circulating within the tube 48, heats the air entering through the air inlet 3 and the mixture as it passes through the Venturi tube 6; and said tube, moreover, provides a hot surface upon which the jets of liquid fuel issuing from the apertures 18 impinge, thereby assisting the vaporization of said fuel.

An auxiliary air inlet 51, Figs. 2 and 3, may be provided in the side of the body 1 for admitting air to the mixing chamber 5 in greater quantity than can be supplied by the inlet 3 and the restricted position of the Venturi tube 6, such auxiliary air inlet being well known in the art. I prefer to control said auxiliary air inlet by a plurality of interconnected shutters 52, each having an arm 53, and all said arms being pivotally connected with a suitable operating rod 54.

It will be seen from the foregoing that my device incorporates in the carburetor itself the functions usually performed by a separate so-called vacuum tank, such functions being controlled directly by the carburetor float 10 and its stem 11. It will also be understood that my device can readily be applied to an existing carburetor merely by substituting the chambers 25 and 27 for the usual

cover of the float chamber 2, and by substituting a new stem 11 for the usual needle valve stem associated with the float.

Having thus described my invention 5 what I claim as new and desire to protect by Letters Patent of the United States is:—

1. A self feeding carburetor comprising a body having a mixing chamber and a communicating float chamber; a pair of receptacles associated with said float chamber, one having a liquid inlet and a suction connection and the other having a liquid inlet leading from the first mentioned receptacle and a liquid outlet leading to said float 10 chamber; a float within said float chamber; and means operated by said float for controlling said suction connection and said liquid outlet.

2. A self feeding carburetor comprising 20 a body having a mixing chamber and a communicating float chamber; a pair of receptacles associated with said float chamber, one having a liquid inlet, a vent, and a suction connection, and the other having a liquid inlet leading from the first mentioned 25 receptacle and a liquid outlet leading to said float chamber; means for preventing back flow of liquid from the second to the first receptacle; a float within said float chamber; and means operated by said float for controlling said suction connection, said vent, and said liquid outlet.

3. A self feeding carburetor comprising 35 a body having a mixing chamber; a float chamber communicating therewith, and a liquid supply chamber positioned above said float chamber, said supply chamber having a liquid inlet, a suction connection, and a liquid outlet leading to said float chamber, a float within said float chamber, a valve 40 stem operated by said float and extending movably through said float chamber and

said supply chamber; valve heads carried by said stem for controlling said suction connection and said liquid outlet; seat members with which said valve heads cooperate; and means for separately adjusting the positions of said seat members.

4. A self feeding carburetor comprising 45 a body having a mixing chamber, a float chamber communicating therewith, and a liquid supply chamber positioned above said float chamber, said supply chamber having a liquid inlet, a suction connection, a vent, and a liquid outlet leading to said float chamber; aligned tubular housings extending respectively from the bottom of said float chamber and the top of said supply chamber; valve seat members mounted in said housings for independent vertical 50 adjustment; a movable stem provided with valve faces adapted to cooperate with said seat members to control said suction connection, said vent, and said liquid outlet; and a float within said float chamber for operating said stem.

5. In a carburetor having a float chamber and a float therewithin, a receptacle adapted to be secured to the upper end of said float chamber and having a liquid supply chamber communicating therewith; a second receptacle adapted to be secured to the upper end of the first receptacle and having a suction chamber provided with a liquid inlet, a suction connection, and a 75 liquid outlet leading to said supply chamber; and means operated by said float for controlling said suction connection and the feeding of liquid from said supply chamber to said float chamber.

In testimony whereof I have signed my name to this specification.

HOWARD E. MARSH.
